UNITED STATES PATENT OFFICE.

FREDRICK E. WENZEL, OF LA CROSSE, WISCONSIN.

LABELING-MACHINE.

SPECIFICATION forming part of Letters Patent No. 730,424, dated June 9, 1903.

Application filed September 6, 1902. Serial No. 122,335. (No model.)

To all whom it may concern:

Be it known that I, FREDRICK E. WENZEL, a citizen of the United States, residing at La Crosse, county of La Crosse, and State of Wisconsin, have invented certain new and useful Improvements in Labeling-Machines, of which the following is a specification.

My invention relates to that class of machines in which bottles are labeled as they are carried on an endless carrier through the machine.

The objects of the invention are to provide a labeling-machine which will apply the body and neck labels to the bottles in an expeditious and efficient manner; also, to provide such a machine with means for applying either the long or the short neck-labels, to provide a simple and efficient label-carrying mechanism, to provide a bottle-holder with means for automatically opening and closing it as it is moved through the machine by its carrier, and also to provide means for rotating the bottle-carrier at stated intervals to bring it into proper position for the label-affixing devices; also, to provide a simple and effective label-feeding mechanism coacting with the label-carrier and paste-supplying mechanism. These and other objects I accomplish by the construction shown in the accompanying drawings, in which—

Figure 1 is a side elevation of my improved labeling-machine. Fig. 2 is an enlarged perspective of one set of body-label-applying mechanism. Fig. 3 is a detail view of one paste receptacle and roller. Fig. 4 is a detail rear elevation of the wipers for the body-labels and a bottle about to pass between them. Fig. 5 is a plan view of the operating gearing and shafting. Fig. 6 is an enlarged plan of one of the bottle-holders with a portion of the endless carrier and frame. Fig. 7 is an enlarged sectional front elevation of one of the bottle-holders. Fig. 8 is an enlarged elevation of one of the label-holders and the actuating mechanism. Fig. 8^a is a detail of one of the nuts and screws for actuating the label-followers. Fig. 9 is an enlarged rear elevation of one of the label-carriers. Fig. 10 is a plan of the machine with the label and paste mechanisms removed and showing the progress of a bottle through a machine. Fig. 10^a is a detail view of a por-

tion of one track-rail. Fig. 11 is an enlarged plan view of the label and paste mechanisms. Fig. 12 shows a bottle with the body-labels applied and the neck-label partially applied. Fig. 13 shows the bottle and the neck-label at another stage. Fig. 14 shows the bottle with both labels applied.

The frame of the machine comprises four uprights A, longitudinal side bars A', and cross-bars A².

B B are the endless tracks secured to the pairs of uprights A, and these tracks each comprise upper and lower members B' B', connected at their opposite ends by the curved end sections B². The inner sides of these tracks are provided with endless grooves b, in which travel the ends of the slats or cross-pieces C' C'. The purpose of these slats is to keep the bottle from tilting backward or forward, and they are secured at intervals to the endless chains C C by means of suitable clips or fastenings c c. The ends of these slats are provided, preferably, with rollers c' c' to run in the track-grooves b. (See Fig. 6.) These carrier-chains pass around sprocket-wheels 1 1, mounted on shafts 2 3, journaled in bearings on the ends of the frame and constitute the endless carrier for the bottle-holders to be presently described. The bearing 4 of shaft 3 is mounted on two guide bolts or rods 5 5 and is adjustable thereon by means of the set-screw 6, having a ball-and-socket connection 7 at its outer end with the middle 85 of bearing 4, so that by turning said set-screw the bearing may be moved to regulate the tension of the endless chains C C, and when properly adjusted the screw 6 will be locked by a nut 8. (See Fig. 1.)

Power is applied to the sprocket-wheel 9 on shaft 2 from the main shaft E by means of a sprocket-chain E' and a sprocket-wheel E². The main shaft E is provided with fast and loose pulleys e e'.

In the lower part of the frame are two alined line-shafts E³ E⁴, geared together and to a counter-shaft F by bevel-gears f f' f², and the shaft E³ is geared to the main shaft by bevel-gears e² e³, while the shaft E⁴ is geared to a second counter-shaft F' by bevel-gears f³ f⁴. (See Fig. 5.)

The endless carrier C C is provided between every pair of slats C' C' with a bottle-

holder D, so that there is an endless series of bottle-holders traveling through the machine between the tracks.

Each bottle-holder D comprises a centrally-apertured cross-bar or bed-piece D', provided at each end with an arm d', secured to the chains C C by means of clips c and beyond which clips said arms are provided with rollers d², which travel in the track-grooves b. On a central cross-bar d³ on the upper side of the cross-bar d' is the rotary clamp-carrier D², to which is secured the upper end of a shaft d⁴, extended down through the central aperture in cross-bar D' and having a gear-wheel 15 d⁵ on the low end.

The clamp-carrier D² is provided at its ends with pairs of arms d⁶, which rest loosely on top of the chains C C to prevent the clamp-carrier from rotating when bottle-carrier is 20 not in channeled-out places in frame, and these arms d⁶ d⁸ do not enter the track-grooves b, as will be seen in Fig. 6.

On top of the clamp-carrier D² are the bottle-clamping jaws D³, which are pivoted at 25 their rear ends, as shown at d⁷, to move toward and from each other and clamp the base of a bottle between them. For this purpose the adjacent faces of the clamping-jaws are recessed, and these recesses are provided with 30 bushings d⁹ of some yielding material, such as rubber, and when so clamped the bottle rests upon the clamp-carrier D².

The free ends of the jaws D³ are forced apart by means of an expansion-spring d¹⁰, 35 mounted on a pin d¹¹, and the jaws are held closed against the action of said spring by means of a spring-catch D⁴, secured to one jaw and having an aperture engaging a pin or catch d¹² on the other jaw. (See Figs. 6 40 and 7.) The free end d¹³ of this catch projects beyond the outer side of the jaw into the path of a releasing lug or arm D⁵ at the rear of the machine, so as to lift the catch out of engagement with the pin d¹¹ and permit the jaws to spring apart and release the bottle. These jaws D³ are also automatically closed upon a bottle by means of the 45 rollers D⁶ D⁸, secured to opposite sides of the forward ends of the tracks, as shown in Figs. 50 1, 10, and engaging the rear outer rounded corners of the jaws as they pass and forcing them into closed position around the bottle.

G indicates the label mechanism for the body-label, and comprises two curved tracks 55 G' G', formed of angle-iron and mounted on top of the tracks B B, the tracks extending upwardly and rearwardly from points just in rear of the jaw-closing rollers D⁶, and these tracks G' G' are supported at their upper rear 60 ends by the standards g, and braced thereto by cross-pieces g' g².

G³ is the label-carrier, pivoted between the outer ends of two vertically-swinging slotted levers G⁴ G⁴, pivoted at their rear ends to the 65 lower ends of the standards g g².

The label-carrier G³ is formed of two end pieces g³ g³, to which the levers G⁴ are pivoted,

and in these end pieces at opposite sides of their pivots g⁴ are mounted the rollers or wheels g⁵ g⁵, which travel along the tracks G' 70 as the levers G⁴ are swung up and down. Extending inwardly from the end pieces g³ g³ are pairs of arms g⁶, and these arms are connected by an arched brace g⁷. (See Figs. 2 and 9.)

G⁵ indicates the label-carrying plates, adjustable toward and from each other for bottles of varying diameters by means of parallel slotted arms g⁸ and screws g⁹. On the rear faces of these plates or bars G⁵ are the 80 vertical ribs g¹⁰ for a purpose to be presently described. When the label-carrier G³ is in its lowest position, it will be held perpendicular (see Fig. 2) by means of two guide posts or lugs B⁵, projecting up from the rails B', in 85 which position it will hold the label across the space between its plates G⁵ for the bottle to engage as it is carried rearwardly.

The levers G⁴ are rocked by means of rods H H, provided at their forked upper ends 90 with rollers h, which enter the lever-slots, while similar rollers h' on the lower ends of the rods engage cams H' on the ends of counter-shaft F'. The rods H are guided vertically in the bearings h² and are held down on 95 the cams by means of the spiral springs h³.

I is the vertically-movable paste-box, having supporting-bars I', provided with pairs of depending guide-arms i, mounted in the upper braces or cross-pieces g' and provided 100 thereabove with supporting-collars i' and below the braces with spiral springs i² to return the box to its normal position. Within the paste-box is mounted a shaft i³, having a pair of distributing-rollers i⁴ and a scraper i⁵, provided with an adjusting-screw i⁶, whereby 105 the amount of paste carried up by the rollers may be regulated.

I² is a rock-shaft, provided with upwardly-extending curved arms i⁶, projecting under the paste-box and having a downwardly-projecting operating-arm i⁷, engaged by a pin or lug i⁸ on a vertically-sliding rod I³, mounted in bearings in the braces g' g² at one side of the frame and provided at its lower end with 115 a roller i⁹ in the path of a cam-lug D⁹ on the left side of the bottle-holder D. This cam-lug D⁹ raises the rod I³, which in turn rocks shaft I² to raise its arms i⁶ and elevate the paste-box so that its rollers will be in the path 120 of the paste-ribs g¹⁰ of the label-carrier G³ when the same is raised by the rods H.

J is the body-label holder in rear of the paste-box and mounted in the same way to move vertically. The label-holder is provided 125 with supporting-bars J', depending guide-arms j, having supporting-collars j', and spiral springs j², and the label-holder is raised by a rock-shaft J², having curved arms j⁶, engaging the lower side of label-holder, and 130 arms j⁷, engaged by a pin or lug j⁸ on the upper part of a vertically-sliding rod J³, which rod has a roller j⁹ on its lower end in the path of a cam-lug D¹⁰ on the right side of the bottle-

carrier D, the rod J³ being in rear of the other rod I³. By this construction the label-holder J will be raised after the paste-box to bring its top label up against the paste-carrying ribs g¹⁰ g¹⁰, the paste-box I having been lowered to its normal position in the meantime by reason of lug D⁹ passing from under its rod I³, and the label-holder J will be lowered in like manner. The label-carrier D will now be brought down behind the guide-lugs B⁵, in which position the label will be held vertically edgewise across the path of the bottle.

K K are flexible label-wipers immediately in rear of the label-holder and against which the bottle carries the label L, which is wiped around it by said wipers. (See Figs. 2 and 4.) These wipers comprise standards or frames k k at opposite sides of the machine and provided with inwardly-projecting sheets of yielding material k' k'.

Holders D are so spaced and above mechanisms are so timed that a label will be brought down into position for every bottle, and the cam H' is so formed that its flattened point of greatest diameter will engage and hold rod H up and so hold the label-carrier G³ over the label-box J while said box is being raised to bring a label up to the paste-carrying ribs g¹⁰.

The labels are moved upwardly in the holder J by means of a follower J⁴, extending through slots in the box and provided on its outer ends with ratchet-nuts j¹⁰ of any suitable construction and through which pass the vertical screws J⁵, swiveled at their upper and lower ends to the label-holder. These screws J⁵ and nuts j¹⁰ raise the follower J⁴ and the labels resting thereon, and when it is desired to lower the follower it is simply necessary to push it down, as the ratchet-nuts allow of such movement, as is well understood. The screw-shafts J⁵ are provided at their lower ends with worm-wheels J⁶ J⁶, between which extends a worm J⁷ on a shaft J⁸, provided at one end with a ratchet-wheel J⁹. (See Figs. 8 8^a.) This label-actuating mechanism is all carried by the label-holder and moves up and down with it, and the ratchet-wheel J⁹ is turned the distance of one tooth or far enough to keep one label exposed at the top of the holder J by means of a pawl J¹⁰, pivoted to an arm or bracket J¹², so as to swing up when the ratchet-wheel moves up with the holder, but to remain rigid when the ratchet-wheel moves down and so turn it, as above described.

It will be seen that by the above-described mechanism a bottle may be placed on the holder D at the front of the machine and that the jaws will be closed on the bottle by the rollers D⁶ and that the bottle will then pass between the members G⁵ of the label-holder and carry the body-label back against the wipers K, which will wipe the label around the bottle and cause its ends which are supplied with paste by the ribs I to adhere to the bottle. As the bottle-holder D moves rearwardly the lugs D⁹ D¹⁰ will raise the paste-

box I and label-holder J and the cam H' will raise the label-carrier and return it with a label in time for the next bottle. When the labeled bottle reaches the rear end of the machine, it will be released by means of the releasing-arm D⁵, which lifts the catch D⁴ out of engagement with the pin d¹¹, whereupon the spring d⁹ will throw the jaws D³ open and release the bottle.

G^X is a second label-applying mechanism constructed like that just described and located in rear thereof and in a higher plane, so as to apply neck-labels to the bottles after their body-labels have been applied.

The neck-labeling mechanism G^X being the same as the body-labeling mechanism will only be briefly described, as follows: G^X is the label-carrier; G^{4X}, the operating-levers therefor; H⁴, the rods for rocking said levers, and H⁵ the cam for reciprocating said rods. These rods H⁴ H⁴ will be made adjustable in any suitable manner, so as to properly regulate the throw of levers G⁴ G⁴. I^X designates the paste-box; I^{8X}, its actuating-rod. J^X is the label-holder, and J^{8X} its actuating-rod.

After a bottle has been supplied with a body-label it will be carried along to the neck-labeler, where a neck-label will be applied. If the neck-label is a short one, it will be applied to the bottle without rotating the latter; but where long neck-labels are used, as shown at L', Figs. 12 to 14, the bottle must be rotated, as will now be described, and the label-carrier will have four paste-carrying ribs g^{10X}, and the paste-rollers i^{4X} will be proportionately lengthened, so that the long labels will be gummed in four places instead of in two places. (See Fig. 11.) Of course the label-holder will be correspondingly lengthened, as is also shown in Fig. 11.

In order that the bottle may be rotated after it passes the body-label wipers K and before it reaches the neck-label holder, I provide a rack R in the path of the gear-wheels d and secured adjustably to one of the upper rails B' by means of slots r and screws or bolts r'. The upper sides of the rails are cut away, as shown at b¹⁰, so that when the gear engages the rack R and rotates the bottle-holder space will be formed to allow the ends d⁶ to clear the rails.

The rack R and gear d⁵ are so proportioned that the bottle-holder will be given a half-turn, thereby to make the back of the bottle-neck face the neck-label holder and cause it to engage the label, as in Fig. 12, and then carry it against the second set of wipers K K. After this the gear d⁵ engages rack R', which gives it a quarter-turn, and so turns the bottle at the first oscillating wiper K⁵, which wipes one end of the label around the neck, as shown in Fig. 13, after which a longer rack R² rotates the gear d⁵ in an opposite direction to rotate the bottle at the second oscillating wiper K⁶, which wipes the other end of the label around the neck, as shown in Fig. 21. This last rack R² is of a length to turn the bottle-

holder far enough to restore it to its original position, and thereby bring its bottle-clamps in position for release of their catch D^4 by the arm D^5 . All three of these racks $R R' R^2$ are provided with the slots and set-screws, and when they are moved back out of the way of gear d^5 the open spaces b^{10} at every rack will be filled by the filling-strips b^{11} . (See Fig. 10^a.)

The oscillating wipers $K^5 K^6$ are mounted at opposite sides of the machine on the top rails and are provided with slotted operating-arms $k^5 k^6$, engaged by rollers on the upper ends of the sliding rods $k^7 k^8$, engaging at their lower ends with oppositely-arranged cams $k^9 k^{10}$ on the ends of the shaft F. These cams rock the wipers in succession as the bottle is brought into position relative thereto in order to bring the curved brushes $k^{11} k^{12}$ down to the bottle-neck in position for wiping the label ends therearound.

The operation is as follows: The shaft E is set in motion, whereupon the various parts begin their movements, as above described. The operator at the front end of the machine places a bottle in the holder D just before it reaches the rollers D^6 , whereupon the rollers will close the clamping-jaws upon the bottle, which will now pass on to the front or body-label carrier, which will hold a label in its path, said label-carrier having made its upward movement to and return movement from its paste-box and label-holder through the action of the rods H and cams H' and the paste-box and label-holder having been elevated into the path of the label-carrier by their rods I³ J³ and the cams D⁹ D¹⁰ on one of the preceding bottle-holders and then dropped back after the said cams D⁹ D¹⁰ have passed from under the rods. The holder containing the bottle now passes through the label-carrier and carries the label with it through the front pair of flexible wipers, which wrap it or bend it around the bottle and cause its pasted or gummed ends to become attached to the bottle. The holder, with the bottle, now reaches the first rack R, which gives the holder a half-turn to the left and causes the bottle to face in the opposite direction, and in this position the bottle-neck will be brought against the neck-label held in the neck-label carrier, which has gone through the same operation as the body-label carrier. The bottle-holder proceeds, and the rear set of flexible wipers K will bend the long neck-label into U shape from rear to front on the bottle-neck, after which the bottle-holder reaches the rack R', which gives it a quarter-turn to the right, and at the same time the curved brush k^{11} has been brought into position and one end of the label wiped into place on the neck. After passing the rack R' the bottle-holder comes opposite to the third rack R², which gives it a three-quarter turn to the left, and the rear wiping-brush k^{12} comes simultaneously into action and wipes the other end of the neck-label in place. The bottle-holder is now restored to its original position and pro-

ceeds rearwardly with the bottle, which is released, as before stated, by the releasing-arm D⁵ lifting the catch D⁴ of the bottle-clamp. 70

Where short neck-labels are to be applied, the racks R R' R² are moved out of the path of the bottle-holder gear d⁵ and a short-label holder and paste-box like those for the body-label will be employed. Where no neck-labels are to be applied, the mechanism G^x will be thrown out of action, as by raising the several operating-rods out of the path of their cams. 75

I do not restrict myself to the exact mechanisms illustrated, as they may be considerably varied within the scope of my invention, nor do I restrict the use of the machine to bottle-labeling, as it is obvious that articles other than bottles may be labeled thereby or 85 with very slight changes in the present mechanism.

What I claim is—

1. The combination with an endless horizontally-traveling carrier, provided with a plurality of bottle-holders to engage the bottoms of the bottles, a paste mechanism over the said endless carrier, and a label-holder in rear of said paste mechanism, of a forked or divided label-carrier, pivoted levers to the free ends of which the label-carrier is pivoted and means for causing the label-carrier to travel horizontally over the paste and label mechanisms and on its return with a label, present it vertically endwise across the path of the bottles. 95

2. The combination with an endless horizontally-traveling carrier provided with a plurality of bottle-holders to engage the bottoms of the bottles, a vertically-movable paste mechanism over the said endless carrier, and a vertically-movable label-holder in rear of said paste mechanism, of a forked or divided label-carrier, pivoted levers to the free ends of which said label-carrier is pivoted, means for causing the label-carrier to travel horizontally over the paste mechanism and label-holder and on its return with a label, present it vertically edgewise across the path of the bottles, and mechanism for operating the paste and label-holding mechanism. 105

3. The combination with a plurality of traveling bottle-holders each provided with jaws for clamping the bottom of a bottle, a catch for locking the jaws together around a bottle, and means for automatically closing the said jaws and means for automatically releasing said catch, of a label-carrier, and paste and label mechanism therefor, substantially as set forth. 110

4. The combination with a plurality of traveling bottle-holders, of a labeling mechanism comprising a label-carrier, mechanism for operating the carrier toward and from the path of the bottle-holders, a vertically-movable paste mechanism, means for raising the same into the path of the label-carrier to apply paste to it, a vertically-movable label-supply in rear of the paste mechanism, means for raising the 115

- label-supply to the overlying paste-supplied surface of the label-carrier, means for returning the label and paste supply devices to their normal position prior to the return movement 5 of the label-carrier, and means for wiping or wrapping the label upon the bottle as it is carried through the label-carrier.
5. The combination with a plurality of traveling bottle-holders, of a labeling mechanism 10 comprising a label-carrier, means for moving the label-carrier toward and from the path of the bottle-holders, a paste mechanism and label-supply, means for moving the same into and out of the path of the label-carrier, a feed 15 mechanism for the label-supply, means for actuating said feed from the movement of said label-supply, and means for affixing the label upon the bottle as the latter is carried through the label-carrier, substantially as described. 20
6. The combination with a plurality of horizontally-traveling bottle-holders, of front and rear label-carriers mounted over the said bottle-holders in different horizontal planes and 25 movable toward and from the paths in which the bodies and necks of the bottles travel, means for actuating said label-carriers in harmony, a paste and label supply over the bottle-holders for each label-carrier and co- 30 acting therewith to first supply the paste and then the labels, and means for wiping or smoothing the labels on the bottles when the bottles pass through the carriers, substantially as described. 35
7. The combination with a plurality of traveling bottle-holders, of levers each swinging in a vertical plane, at opposite sides of the path of the bottle-holders, mechanism for actuating the said levers, a label-carrier pivoted to the free end of said levers and having spaced paste-receiving surfaces to engage a label and hold it across the path of the bottles, curved tracks on which the label-carrier runs, guides at the lower ends of the tracks 40 to hold the label-holder and label vertically edgewise and vertically-movable paste and label supply mechanisms at the upper ends of the tracks to supply paste and labels in succession to the label-carrier, substantially 45 as described. 50
8. The combination with a plurality of traveling bottle-holders, of levers each swinging in a vertical plane and pivoted at opposite sides of the path of said holders, a label-carrier in two spaced sections at the outer ends of said levers; each section having on its rear face a paste-receiving surface, upwardly and rearwardly curved tracks for the label-carrier and means for operating the levers, a label and a paste supply mechanism at the upper ends of the tracks over which the label-carrier travels, substantially as described. 55
9. The combination with a plurality of horizontally-traveling bottle-holders, of levers 60 swinging in a vertical plane pivoted at oppo- site sides of the path of said holders, a label-holder at the free ends of said levers and formed in two spaced adjustable sections between which the bottles are adapted to pass, upwardly and rearwardly curved tracks for 70 the label-carrier and a label-supply mechanism at the upper end of the tracks, substantially as described. 75
10. In a labeling-machine, a label-carrier comprising a yoke, a carrier-section at each end of the yoke having rollers and provided with parallel plates or members adjustable toward and from each other and a track for said rollers, substantially as described. 80
11. A labeling-machine comprising an endless series of bottle-holders, a driving mechanism therefor, a label mechanism mounted above the path of the holders, and comprising curved tracks, a label-carrier traveling thereon toward and from the bottle-holders, pivoted levers to the outer ends of which said label-carrier is connected, operating-rods connected at their upper ends to said levers, a shaft having cams engaging the lower ends of said rods and vertically-movable paste and label boxes at the upper ends of the curved track and provided with operating-rods actuated from the bottle-holders to raise the paste and label devices into the path of the label-carrier, substantially as described. 85 90
12. In a labeling-machine the combination with the traveling bottle-holders, of the upwardly and rearwardly movable label-carrier, and means for moving it toward and from the bottle-holders, of paste and label boxes or 100 holders, in the upper rearward path of the label-carrier, rock-shafts having arms engaging the paste and label boxes to raise them, and vertically-reciprocating rods in operative connection with the said rock-shafts and actuated successively from said bottle-holders, 105 substantially as described. 95
13. In a labeling-machine, the combination with the traveling bottle-holders having cam-lugs on opposite sides, of a label-carrier, means 110 for moving it toward and from the bottle-holders, paste and label holders in the upper rearward path of the label-carrier, rock-shafts having arms engaging said paste and label boxes to raise them, springs for retracting 115 said boxes, and rods operatively connected at their upper ends with said rock-shafts and extending at their lower ends into the paths of said cam-lugs, substantially as described. 120
14. The combination with the rotary traveling bottle-holders, of body and neck labeling mechanisms one in advance of the other and adapted to bring the labels in the path of the body and neck of the bottle, means for imparting rotary motion to the bottle-holders 125 between the two labeling mechanisms, to present the rear of the bottle-neck to the middle of the neck-label, neck-label wipers to engage the ends of the neck-labels and means adjacent to each of the said wipers to rotate 130

the bottle-holder in opposite directions and restore it finally, to the same normal position, substantially as described.

15. The combination with rotary traveling 5 bottle-holders each having an operating-shaft provided with a gear, of the body and neck labeling mechanisms one in advance of the other to supply the body and neck labels in the paths of the bodies and necks of the bottles, wipers in rear of the neck-labeling mechanisms having curved brushes at their upper ends to engage the ends of the neck-labels, and three alternately-arranged racks located in the paths of the gears on the shafts of said 15 bottle-holders to rotate the same for the purposes set forth.

16. The combination with the traveling bottle-holders each having an operating-shaft provided with a gear, of the body and neck 20 labeling mechanisms one in advance of the other to supply the body and neck labels in the paths of the bodies and necks of the bottles, rocking wipers at opposite sides of the machine in rear of the neck-labeling mechanism and having curved brushes at their upper ends to successively engage the ends of the neck-label, means for actuating the 25 said rocking wipers, in harmony with the travel of the bottle-holders, racks in the path 30 of the bottle-holder gears for rotating the bottle-holders in the manner described in advance of the neck-labeler, and at each rocking wiper; the said racks being adapted to be moved out of the path of said gears, substantially as set forth.

17. In a labeling-machine, a bottle-carrying mechanism comprising, the endless tracks, endless chains having pairs of slats with their ends in said tracks, bottle-holders provided 40 with base members secured to the chains between every pair of slats and having their ends projecting into said tracks, a clamp-carrier secured to each base-piece and having projections resting freely on the chains and 45 terminating exterior to the tracks, and clamps mounted on the upper sides of the clamp-carriers to grasp the base of the bottle.

18. In a labeling-machine, a bottle-carrying mechanism comprising the endless tracks 50 having cut-away portions on its upper side, sprocket-wheels, endless chains on the wheels and provided with pairs of slats extended at their ends into said tracks, and bottle-holders comprising base-pieces secured to the chains 55 between the pairs of slats with their ends entering said track, clamp-carriers mounted on the base-pieces with their ends overlying the chains exterior to the tracks, pivoted clamps on said clamp-holders, and a locking device 60 to hold the clamp closed upon the base of a bottle, a shaft secured to the clamp-carrier and extended down through the said base-

piece and there provided with a gear, and racks for actuating said gear, substantially as described.

19. In a labeling-machine, a bottle-carrier provided on its upper side with clamps to grasp the base of a bottle and hold it vertically, springs to separate the clamps and a spring-catch to hold the clamps in their closed 70 position, substantially as described.

20. A labeling-machine, comprising the endless tracks, the sprocket-wheels, the endless chains, the bottle-holders carried thereby and having automatically-operated clamps to 75 grasp and release the bottles, a drive-shaft geared to one of the sprocket-wheels, two counter-shafts geared to the drive-shaft and provided with cams at their ends, front and rear labeling mechanisms each having a paste 80 and label supply and a label-carrier, pivoted levers to which said label-carriers are pivoted and adapted to carry gummed labels down into the path of the bottles, rods extended down from said pivoted levers to the cams on 85 one of said counter-shafts, flexible wipers in rear of the lowest position of the label-carriers, and rocking wipers in rear of the rear labeling mechanism and provided with operating-rods engaging the cams on the rear 90 counter-shaft, substantially as described.

21. In a labeling-machine, the combination with the vertically-movable label-box open at its top and provided with a follower, of screw-shafts engaging the ends of the follower, 95 worm-gears on the lower end of the screw-shafts, a worm-shaft provided with a worm meshing with said worm-gears, a ratchet-wheel on said shaft and a pawl mounted independent of the label-box and engaging the 100 ratchet-wheel to rotate it when the label-box moves down and yield when the box moves up, substantially as described.

22. In a labeling-machine, the combination with the vertically-movable label-box open at 105 its top and provided with a follower having ratchet-nuts at its ends, of screw-shafts swiveled to the label-box and passing through said nuts to raise the follower and allow it to be pushed down, worm-gears on the lower 110 ends of the screw-shafts, a worm-shaft having its worm meshing with said worm-wheels and provided with a ratchet-wheel, and a pawl 115 engaging said ratchet and pivoted to a stationary support beyond the label-box to yield as the box moves up and actuate the ratchet as the box moves down, substantially as set forth.

In testimony whereof I affix my signature in presence of two witnesses.

FREDRICK E. WENZEL.
